UNITED STATES PATENT OFFICE.

LEWIS C. PARKER, OF ROBINSON, KANSAS.

IMPROVEMENT IN SUGAR-SAFES.

Specification forming part of Letters Patent No. **178,947**, dated June 20, 1876; application filed April 18, 1876.

To all whom it may concern:

Be it known that I, LEWIS C. PARKER, of Robinson, in the county of Brown, and State of Kansas, have invented a new and Improved Sugar-Safe, of which the following is a specification:

My improved sugar-safe consists of a can of sheet metal, or other suitable materials, having an annular chamber around the top for holding water to moisten the air above the sugar, and prevent the sugar from drying and packing in the can, the said chamber being open to the space in the can below the cover, so that the vapor evaporated from the water may escape into the space. In addition to the evaporating-chamber, the cover is made to fit on with rubber packing to prevent insects and dirt from getting in; also to prevent the vapor from escaping.

Figure 1 is a sectional elevation of my improved sugar-safe. Fig. 2 is a horizontal section.

A is the can, which will be made of galvanized sheet-iron, or any other suitable material. B is the annular water-chamber, attached to the upper part below the cover, and,

by preference, located on the inside of the cylinder; but it may be on the outside, if preferred. C represents a row of holes opening from the chambers into the can for the escape of the vapor. D represents the hole for filling the said chamber, being, by preference, closed on the top. E is the cover, and F is a packing of rubber attached to the cover for closing the can tight, said packing being arranged a little tapering to fit in the can tightly. G is a faucet for drawing off the water from the evaporating-pan when required.

Having thus described my invention, what I claim as new, and desire to secure by Letters Patent, is—

1. The combination of an evaporating pan or chamber, B, with a can, A, substantially as specified.

2. The combination of a cover having flexible packings F and an evaporating-pan, B, with a can, A, substantially as specified.

LEWIS C. PARKER.
